WILLIAM L. MYERS, OF NEWARK, AND GEORGE D. HARRISON, OF BELLEVILLE, NEW JERSEY, ASSIGNORS TO L. A. MYERS, JR., INC., OF NEWARK, NEW JERSEY, A CORPORATION OF NEW JERSEY

BUCKLE

Application filed September 18, 1930. Serial No. 482,666.

Our invention relates to improvements in buckles intended primarily for use on shoes and it is our object to produce a buckle which can be easily threaded, easily sewed 5 to a strap, which will have a short tongue and which will present a neat appearance on the shoe.

In the drawings we have illustrated one form of our invention but the details may 10 be varied without departing from our invention. Fig. 1 is a view of our buckle with the straps thereon; Fig. 2 a view of our buckle with one strap sewed thereto; Fig. 3 a sectional view of the structure of 15 Fig. 2 on the line 3—3 thereof; and Fig. 4 an edge view of our buckle.

The buckle comprises a pair of closed loops 1 and 2, those shown being oval, although any desired form may be used and 20 they may be plain or suitably ornamented, the slots in the outside edges of the buckle illustrated being simply for ornamental purposes. These loops are connected by bars 3 and 4 inclined with respect to each other 25 so that they meet one side of the loop 1 in a substantial V in the point of which the short tongue 5 is hinged with its free end adapted to bear on the opposite side of the loop 1. The bars 3 and 4 are more widely 30 separated where they meet the side of the loop 2 so that the side of the loop 2 between the bars 3 and 4 serves as a sewing bar to which one of the shoe straps *s* is attached.

In use the strap *s* on one side of the shoe 35 is sewed to the sewing bar and the free end of the strap *s'* on the other side of the shoe is passed through the loop 1 from rear to front, a hole therein engaging the tongue 5, after which the free end is passed through 40 the loop 2 from front to rear. As the loops are closed the threading operation is easy and the tongue, being short, is easily engaged and disengaged. The tongue, being in the point of the V is always centered in the 45 buckle frame.

We claim:—

1. In a buckle, an integral, rigid frame comprising a pair of spaced strap engaging loops, a pair of spaced bars connecting the 50 adjacent sides of said loops, the side between

the connecting bars on one loop serving as a sewing bar for a strap, and a tongue hinged to the other loop on the side between the connecting bars with its free end adapted to bear against the opposite side of said 55 loop.

2. A buckle comprising a pair of closed loops, a pair of bars inclined with respect to one another connecting adjacent sides of 60 said loops, a tongue hinged to one side of one loop between the narrowly separated ends of the connecting bars, the side of the other loop between the widely separated 65 ends of the connecting bars serving as a sewing bar for a strap.

In testimony whereof we have hereunto 70 subscribed our names.

WILLIAM L. MYERS.
GEORGE D. HARRISON.
